United States Patent

Des. 236,640
Patented Sept. 2, 1975

236,640

GAME BOARD

Stanley J. Kolwicz, 16 Sanford Ave.,
Emerson, N.J. 07630

Original design application June 28, 1972, Ser. No.
267,164, now Patent No. 233,053. Divided and this
application July 22, 1974, Ser. No. 490,740

Term of patent 14 years

Int. Cl. D21—01

U.S. Cl. D34—5 SS

FIG. 1

FIG. 2

FIG. 3

FIG. 1 is a perspective view of a game board showing my new design;

FIG. 2 is an end elevation view thereof; and

FIG. 3 is a top plan view thereof.

This is a division of design application D. 267,164, filed June 28, 1972, now Design Pat. D. 233,053.

I claim:

The ornamental design for a game board, substantially as shown and described.
